UNITED STATES PATENT OFFICE.

PHILIP J. KENT, OF ROYAL OAK, MICHIGAN, ASSIGNOR TO CHRYSLER CORPORATION,
OF DETROIT, MICHIGAN, A CORPORATION OF DELAWARE.

DESIGN FOR AN AUTOMOBILE INSTRUMENT PANEL.

Application filed April 1, 1927. Serial No. 21,426. Term of patent 14 years.

To all whom it may concern:

Be it known that I, PHILIP J. KENT, a citizen of the United States, residing in the city of Royal Oak, in the county of Oakland and State of Michigan, have invented a new, original, and ornamental Design for an Automobile Instrument Panel, of which the following is a specification, reference being had

to the accompanying drawing, forming a part thereof, in which the figure is a front elevation view of the article showing my new design.

What I claim is:

The ornamental design for an automobile instrument panel, as shown.

PHILIP J. KENT.
